ERNEST RIEMENSCHNEIDER, OF DETROIT, MICHIGAN, ASSIGNOR TO FORD MOTOR COMPANY, OF DEARBORN, MICHIGAN, A CORPORATION OF DELAWARE

CONNECTING PLUG

Application filed September 18, 1929. Serial No. 393,548.

The object of my invention is to provide a connecting plug of simple, durable, and inexpensive construction.

A further object of my invention is to provide a connecting plug for use where a detachable connection between one or more current carrying wires is required.

Still a further object of my invention is to provide a connecting plug especially adapted for use with automobile lamps. Such lamps are usually provided with a reflector having one or more lamp sockets therein. It is general practice to run several wires from these lamp sockets in the reflector to a gang 15 socket in the lamp housing into which a gang plug is detachably secured to complete the electrical circuit. My improved connecting plug is especially adapted for use as a gang connecting plug because several or more electrical circuits may be connected through this 20 plug with very little increase in cost thereof.

Still a further object of my invention is to provide a connecting plug in which no screws, nuts or parts requiring the use of tools to assemble or dismantle are required. In all 25 types of connecting plugs with which I am familiar, either the wires are secured permanently to the sockets or they are held therein by screws or spring connections. In my improved connecting plug no screws or springs 30 type fasteners are used to secure the wires therein and further, the parts are so arranged that the device may be assembled or dismantled without breaking any permanent 35 electrical connection and without the use of any tools whatsoever.

Still a further object of my invention is to provide a connecting plug having the pairs of terminals completing each electric circuit 40 individually urged against each other so that a good electrical contact between the terminals of each circuit may be made independently of the other circuits. In my improved connecting plug each pair of terminals are 45 individually resiliently urged into contact with each other by a helical spring disposed on one of the terminals so that regardless of the number of circuits provided for in the connector a positive electrical connection 50 will be provided for each circuit.

With these and other objects in view, my invention consists in the construction, combination, and arrangement of the various parts of my improved device, as described in the specification, claimed in my claims, and illustrated in the accompanying drawing, in which:

Figure 1 shows a central sectional view through my improved connecting plug.

Figure 2 shows a perspective view of the 60 device shown in Figure 1, the parts being dismantled to better illustrate the construction.

Figure 3 shows an enlarged sectional view through one of the terminals, and

Figure 4 shows an enlarged sectional view 65 through the lamp housing showing the means for securing the connecting plug socket in the housing.

Referring to the accompanying drawing, I have used the reference numeral 10 to indicate generally a lamp housing having my improved connecting plug installed thereon. A sleeve 11 extended inwardly from any convenient part of the housing 10 in position to support the connector plug and socket. I 70 have shown the sleeve 11 extending from the center rear wall of the housing but it may be advisable in some types of lamps to place the sleeve 11 near the bottom of the lamp or at one side thereof.

A socket 12 formed from an open ended tubular member is provided with an insulating cap over one end which is held in position on the socket by projections 14, extending from the cap, co-acting with suitable 85 notches in the socket and by a plurality of ears 15 formed on the socket 12 which are bent down over the rear face of the cap 13. The cap 13 and socket 12 are thus permanently secured together.

A tongue 16 is punched from one side of the socket 12 and is bent outwardly so that it may co-act with an opening 17 formed in the sleeve 11. This construction is illustrated in Figure 4. The socket 12 is assembled in the sleeve 11 by pushing the socket through the sleeve from the inside of the lamp housing until the tongue 16 snaps into the opening 17 in the sleeve 11. The projections 14 extend radially from the socket 12 100

and bear against the end of the sleeve 11 when the tongue 16 is in the opening 17. It may thus be seen that the socket 12 is anchored in the sleeve 11 against rotation or longitudinal movement without the use of any tools whatsoever. When it is desired to remove the socket, the tongue 16 is pressed inwardly and the socket drawn out through the inside of the lamp housing. Where a portable connection is desired it is not necessary to anchor the sleeve 12 in a fixed member such as the housing 10, and it may be left exposed or may be covered with an insulated cap as the user sees fit.

In the accompanying drawing, I have shown terminals for three electrical circuits but it may be mentioned that this device is adapted for either single, double, or in fact, any reasonable number of terminals by correctly proportioning the device.

Three wires 18 are shown extending within the housing 10, but more or less may be used according to the number of circuits provided for. A terminal 19 is soldered at 20 to the end of each wire 18. Bushings 21 are secured in the cap 13 into which the terminals 19 are reciprocally mounted. A spring 22 extends between the soldered end of each terminal 19 and its bushing 21 so that the terminal may be resiliently urged into the socket 12. When two or more wires 18 are used, similar terminals, springs and bushings are provided for each wire which are preferably spaced equally around the periphery of the cap 13.

A cylinder 23, preferably made from insulating material such as molded rubber or bakelite, is provided for securing mating terminals 24 which are fastened on the ends of wires 25 in position to co-act with the terminals 19. When three circuits are used, the cylinder 23 is provided with three slots 26 equally spaced around and extending the length of the cylinder. The inner end of the cylinder 23 is provided with a counterbore 27 aligned with the bottom of each slot 26 to receive the terminals 24. The counterbores 27, being of greater diameter than the width of the slots 26, secure the terminals 24 against radial movement.

To assemble the device it is only necessary to place the wires 25 into the slots 26 and then draw these wires rearwardly until the terminals 24 are seated in the counterbores 27. The terminals 24 are thus held against radial movement and movement towards the rear of the cylinder 23.

The wires 25 are usually manufactured in the form of a multiple conductor having an outer covering 28. An armoured cable 29 is sometimes provided on the covering 28 to give a more pleasing appearance and to protect the cable from damage. When such armoured cable is provided, a sleeve 30 is secured to the end of the cable 29 which is

provided with a flange 31 extending radially therefrom. A coupling sleeve 32 co-acts with the flange 31 to form a water tight connection between the parts when in the assembled position. A pair of bayonet type slots 33 are provided in the socket 12 which co-acts with pins 34 extending inwardly from the coupling 32 so that the latter may be detachably secured to the sleeve 12.

A horizontal groove 35 is provided in the cylinder 23 which co-acts with a suitable notch 36 in the socket 12 so that the cylinder may only be inserted in the socket in one position.

To install my improved connecting plug 80 on a lamp or other device, the socket 12 is first inserted in the sleeve 11, then the wires 25 are placed in the slots 26 of the cylinder 23 and drawn rearwardly so that the terminals 24 are seated in the counterbores 27. The cylinder 23 is then inserted in the socket 12 and secured to the outer end of the socket 12 with the bayonet connection 33.

Among the many advantages arising through the use of my improved device it may be well to mention that as only two relatively sturdy insulating members are used namely, the cap 13 and the cylinder 23, there is very little chance of such insulation breaking down and short circuiting the device. There is no possible chance of the terminals 24 coming in contact with the socket 12 as long as the cylinder 23 remains intact because they are positively held in the counterbores 27 against axial movement. Further, the terminals 19 being held in the bushings 20 are positively prevented from coming in contact with the socket 12.

A further advantage results because no screws or parts which can possibly jar loose are used in the device so that it is especially adapted for use in automobile head lamps or other devices which are subject to vibration.

Still a further advantage results because each terminal is resiliently urged into contact with its mating terminal to secure a good electrical connection independent of the other terminals of the device.

A further advantage results because one size of my improved connecting plug may be standardized and one or any number of circuits conducted through the device with only a slight alteration of the cylinder 23 and cap 13. The majority of the parts are the same for single, double, or triple circuit plugs.

Possibly the greatest advantage, aside from its cheapness of manufacture, results because the device may be assembled or dismantled without the use of any tools whatsoever.

Some changes may be made in the construction, combination, and arrangement of the various parts of my improved device, and it is my intention to cover by my claims such

changes as may reasonably be included within the scope thereof.

I claim as my invention:

1. A connector comprising a housing having a sleeve extending therefrom, an opening in said sleeve, a socket adapted to be received by said sleeve, an insulating cap secured to said socket having a projection extending therefrom adapted to co-act with the end of said sleeve to form a stop for movement of the socket in one direction, and a tongue resiliently extended from said sleeve adapted to co-act with said opening to form a stop for movement of the socket in the opposite direction. 70
2. A connector comprising a socket having a cap secured in one end thereof said cap having a wire terminal reciprocally mounted therein, a cylinder of insulating material secured in the other end of said socket, said cylinder having a peripheral slot therein aligned with said terminal and having a counterbore therein adjacent to said terminal and aligned with said slot and a wire in said slot having a second wire terminal secured thereto and disposed in said counterbore to be thereby held aligned with the first mentioned terminal. 80
3. A connector comprising a socket having a cap secured in one end thereof said cap having a wire terminal therein resiliently urged into said socket, a cylinder of insulating material secured in the other end of said socket said cylinder having a peripheral slot therein aligned with said terminal and having a counterbore therein adjacent to said terminal and aligned with said slot, and a wire in said slot having a second wire terminal secured thereto and disposed in said counterbore to be thereby held in position aligned with the first mentioned terminal. 85
4. A connector comprising a socket having a cylinder of insulating material therein, and an insulated wire having a terminal secured to the end thereof, said cylinder having a peripheral slot extending the length thereof receiving said wire and having a counterbore therein aligned with said slot, the counterbore receiving said terminal to thereby prevent radial movement of the terminal in said cylinder. 100
5. A connector comprising a socket having a cylinder of insulating material therein, and an insulated wire having a terminal of larger diameter than the wire insulation secured to the end thereof, said cylinder having a peripheral slot therein receiving said wire and having a counterbore therein aligned with said slot the counterbore receiving said terminal to thereby prevent radial movement of the terminal in said cylinder. 105
6. A connector comprising a socket having a cylinder of insulating material therein, said cylinder having a plurality of equally spaced peripheral slots therein extending the 110
- length thereof and having counterbores in one end thereof aligned with each of said slots, and insulated wires disposed in said slots each of said wires having a terminal secured thereto and disposed in the aligned counterbore. 115
7. A connector comprising a socket having a cylinder of insulating material therein, said cylinder having a plurality of peripheral slots extending the length thereof and having counterbores in one end thereof aligned with the bottoms of said slots so as to be spaced from the periphery of said cylinder, and wires disposed in said slots having terminals thereon disposed in said counterbores. 120
8. A connector comprising a wire terminal spacer of insulating material and of cylindrical shape having a longitudinal slot in the periphery thereof and having a counterbore therein aligned with said slot so that the wire may be laid in the slot and the terminal drawn into said counterbore to thereby prevent radial movement of the terminal. 125
